DESIGN FOR A MODEL OF AN ARCHITECTURAL UNIT

Wallace K. Harrison, New York, N. Y., and Jacques Andre Fouilhoux, Short Hills, N. J., assignors to New York World's Fair 1939, Incorporated, New York, N. Y., a corporation of New York

Application August 10, 1937, Serial No. 70,972

Term of patent 3½ years

To all whom it may concern:

Be it known that we, Wallace K. Harrison and Jacques Andre Fouilhoux, citizens of the United States, residing respectively at 237 East 81st Street, New York, N. Y., and Short Hills, N. J., have invented a new, original, and ornamental Design for a Model of an Architectural Unit, of which the following is a specification, reference being had to the accompanying drawings, forming a part thereof, in which Fig. 1 is a perspective view of a model embodying our new design; Fig.

2 is a top view of the model; Fig. 3 is a view in partial cross-section taken along the line 3—3 of Fig. 2, certain parts being shown in elevation; Fig. 4 is a cross-sectional view through the bridge at 4—4 in Fig. 2.

We claim:

The ornamental design for a model of an architectural unit as shown.

WALLACE K. HARRISON.
JACQUES ANDRE FOUILHOUX.
